ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

LET-OFF FOR NARROW-WARE LOOMS

Application filed December 5, 1929. Serial No. 411,892.

This invention relates to improvements in let-offs for narrow ware looms and it is the general object of the invention to provide a simplified let-off of the gravity actuated type 5 wherein the release of the tension will not be abrupt but will be gradual to preserve a uniform tension on the warp threads.

In certain forms of narrow ware looms it is customary to train the warp threads extending from the warp spools or beams under a movable weighted pulley arranged to move upwardly as the warp is consumed in the weaving operation. A disk movable between friction pads is sometimes employed in this 10 form of let-off, one or another of the pads being under control of a lever lifted by the pulley as the latter rises. In certain forms 15 of this general type of let-off heretofore employed it is possible for the releasing pad because of the location of the center around which it moves to stick, thereby preventing paying-off of the warp and resultant breaking of the latter. It is an important object 20 of my present invention to provide such an arrangement between the pad and the lever as will effect proper release of the tension.

It is a more particular object of my present 25 invention to provide a friction pad carrying pivoted member to cooperate with the pulley actuated lever wherein yielding means between the lever and the member act so that the latter will not move to cause a sudden release of the tension.

With these and other objects in view which 30 will appear as the description proceeds, my invention resides in the combination and arrangement of parts hereinafter described and set forth in the claims.

In the accompanying drawings wherein a 35 convenient embodiment of my invention is set forth,

Fig. 1 is an end elevation of the upper portion of a narrow ware loom having my invention applied thereto,

Fig. 2 is a horizontal section on an enlarged scale taken on line 2-2 of Fig. 1,

Fig. 3 is a vertical section on line 3-3 of Fig. 2,

Fig. 4 is a vertical section on line 4-4 of Fig. 3, and

Fig. 5 is a detail vertical section on an enlarged scale on line 5-5 of Fig. 4.

Referring particularly to Fig. 1, I have shown a loom frame 10 having secured thereto a top rigging 11 provided with upper and lower stands 12 and 13, respectively, between which extends a supporting carrier or bracket 14 provided with a plurality of rearwardly extending rods or spindles 15. The latter have mounted thereon warp spools 16 and the warp threads are led upwardly from said spools around guides 17 and 18, respectively. The warp extends down from each guide 18 under a pulley 19 and then up over one or more rollers 20 from which they descend to pass under what in effect is a whip roll 21.

Each pulley 19 is mounted on a so-called pulley stock 22 and carries a weight 23. Each pulley stock has extending therethrough a lever 24 and as the warp is used up the pulley stock will be raised to lift the corresponding lever. It is the lifting of the lever under these conditions which ordinarily acts to permit the paying-off of additional 70 warp so that the weight and pulley stock may again descend.

The matter thus far described is common construction, the pulley stock being substantially the same as set forth in my prior Patent No. 1,280,734 and the lever arrangement may be similar to that shown in my prior Patent No. 1,546,582 which shows a disk similar to that designated herein at 25 to be detachably connected to the corresponding 80 spool and rotate with the latter.

In carrying my invention into effect I provide a series of pressed steel brackets one of which is shown in detail in Fig. 2 at 30. Each bracket is secured to the carrier 14 by means of bolts 31 and supports a horizontally extending stud 32. The stud has pivotally mounted thereon a member 33 having a horizontally extending arm 34 which in effect is a saddle U-shaped in section as shown in Fig. 95 5. Each of the levers 24 is pivoted on the stud 32 and passes through the saddle, being adapted to have engagement with the lower horizontal web 35 of the latter.

The member or lever 33 is provided with 100

a depending arm 36 to which is secured the movable friction element 37, which may be a strip of leather 37. The latter has contact with one face of the disk 25 and moves the latter against the fixed friction pad 38 which is secured to the bracket 30.

Extending from the member 33 is a small finger 39 between which and lever 24 is located a comparatively light compression spring 40. The latter is held in position by means of bosses or lugs 41 and 42 carried, respectively, by the arm 39 and lever 24 so as to prevent loss. Any other convenient means of retaining the spring in position may be employed.

In operation it may be assumed that an abundance of warp has been unwound from the spools so that the pulleys 19 are in a relatively low position with the weight 23 supported by the outer end of the lever 24. Under these conditions the lever will overpower spring 40 and act through lever 33 to push pad 37 against the disk to prevent further paying-off of the warp. As weaving progresses and the warp is used up the pulley stock 22 will be raised and in time will lift the lever 24 away from the web 35. At this time the compression spring 40 comes into play and exerts a downward pressure on the horizontal portion of the member 33, tending to hold the pad 37 against the disk 25. As the lever continues to move upwardly the effect of the spring gradually grows less and less until the pressure of the pad 30 is so light as to permit slipping of the disk, whereupon the spool which is caused to rotate with the disk can unwind warp and the pulley 19 will again move downwardly to restore the parts to disk locking position.

I find that it is of considerable importance to have the stud 32 around which the pad moves as near the disk 35 as possible. It is not essential, however, that the spring 40 be used, although its use results in a somewhat smoother action on the part of the disk and friction pads.

From the foregoing it will be seen that I have provided a simple form of let-off wherein the weighted lever and the movable friction member are pivoted about the same stud, the member being formed to have engaging relation with the lever when the latter is down. Furthermore, it will be seen that the spring 40 which is shown herein for convenience as a compression spring prevents a sudden release in the friction exerted by the movable pad when the lever moves away from the web 35. The weight of the lever is sufficient to overpower the spring 40 under ordinary conditions so that as soon as the lever moves away from the web the friction will be reduced an appreciable amount although not entirely so, and the diminution in pressure will be gradual as the lever moves upwardly.

Having thus described my invention it will

be seen that changes and modifications may be made therein by those skilled in the art without departing from the spirit and scope of the invention and I do not wish to be limited to the details herein disclosed, but what I claim is:

1. In a let-off for a narrow ware loom having a warp spool and a disk movable therewith and a friction element to cooperate with the disk, a fixed stud closely adjacent the disk, a lever pivoted to the stud, a second lever pivoted on the stud and adapted to have operative connection with the first named lever when the latter is in low position, friction means carried by the second lever to engage the disk and force the latter against the first named friction when the first lever is down, and means to lift the first named lever as the warp is consumed to break the engagement between the levers and thereby lessen the pressure exerted by the friction means.

2. In a let-off for a narrow ware loom having a warp spool and a disk movable therewith and a friction element to cooperate with the disk, a pair of levers pivotally mounted about a common center which is closely adjacent the disk, said levers being in engagement when sufficient warp is present, a friction surface on one lever to force the disk against the first friction element when the other lever is down, and means dependent upon the shortening of the warp to lift the last named lever out of operative engagement with the first named lever and thereby diminish the friction exerted by the friction surface against the disk.

3. In a let-off for a narrow ware loom having a warp spool and a disk movable therewith and a friction element to cooperate with the disk, a pair of levers pivotally mounted about a common center which is closely adjacent the disk, said levers being in engagement when sufficient warp is present, a friction surface on one lever to force the disk against the first friction element when the other lever is down, means dependent upon the shortening of the warp to lift the last named lever out of operative engagement with the first named lever and thereby diminish the friction exerted by the friction surface against the disk, and resilient means interposed between the levers and operative when said other lever moves out of engagement with the first named lever to exert a pressure against the latter.

4. In a let-off for a narrow ware loom having a warp spool and a disk movable therewith and a friction element to cooperate with the disk, a pair of levers pivotally mounted about a common center which is closely adjacent the disk, means to establish engagement between the levers when one lever is down, a friction member on the other lever to force the disk against the friction element when said first lever is down, and means dependent upon the shortening of the warp to lift the first

named lever out of operative engagement with the other lever and thereby diminish the friction exerted by the friction member against the disk, and resilient means interposed between the levers and operative when the first lever moves out of engagement with the second lever to exert a pressure against the latter, the pressure diminishing as the first named lever moves upwardly.

5. In a let-off for a narrow ware loom having a warp spool and a disk movable therewith and a friction element to cooperate with the disk, a pair of levers pivotally mounted about a common center, means to establish engagement between the levers when one lever is down, a friction member on the other lever to force the disk against the friction element when said first lever is down, and means dependent upon the shortening of the warp to lift the first named lever out of operative engagement with the other lever and thereby diminish the friction exerted by the friction member against the disk, and yielding means interposed between the levers and operative when the first lever moves out of engagement with the second lever to exert a pressure against the latter, the pressure diminishing as the first named lever moves upwardly.

6. In a let-off for narrow ware looms, a warp beam, a disk rotatable therewith, a pair of friction elements between which the disk lies, a pair of pivoted members one of which carries one of the friction elements and the other of which carries the other friction element and is determined as to position by the tension of the warp, and yielding means between the members, the members normally being in operative engagement with each other when sufficient warp has been unwound, and moving out of operative engagement with each other when insufficient warp remains, the yielding means operating to hold the friction pad against the disk when the members are out of operative engagement.

45. 7. In a let-off for narrow ware looms, a warp beam, a disk rotatable therewith, a pair of friction elements between which the disk moves, a pair of pivoted members one of which carries one of the friction elements and the other of which carries the other friction element and is determined as to position by the tension of the warp, and yielding means between the member, the members normally being in operative engagement with each other when sufficient warp has been unwound and moving out of operative engagement with each other when insufficient warp remains, the yielding means operating to hold the friction pad against the disk when the members are out of operative engagement with a force which diminishes as said other member moves upwardly.

In testimony whereof I have hereunto affixed my signature.
